UNITED STATES PATENT OFFICE.

CHARLES BURNHAM, OF LOS ANGELES, CALIFORNIA, ASSIGNOR TO BURNHAM BASKET COMPANY, A CORPORATION OF CALIFORNIA.

BOX-MAKING MACHINE.

1,252,544.

Specification of Letters Patent.

Patented Jan. 8, 1918.

Application filed March 18, 1915. Serial No. 15,252.

To all whom it may concern:

Be it known that I, CHARLES BURNHAM, a citizen of the United States, and a resident of Los Angeles, county of Los Angeles, and 5 State of California, have invented certain new and useful Improvements in Box-Making Machines, of which the following is a full, clear, and exact description.

This invention relates more particularly 10 to machinery for making berry or fruit baskets in which the body is made from veneer shucks and the said shucks folded and held together by a metal binding.

Where the baskets or boxes are of a 15 small size the metal binding may be and in the character of machine invented by me and such as disclosed in my Patent No. 1,119,843, granted December 1, 1914, is made from a single narrow metal strip 20 which is folded substantially rectangular according to the shape of the box or basket and bound thereto, but where the boxes are of a large size as for example what are known as five pound boxes, the machine to 25 handle a single strip would be necessarily large and its feed slow for handling a strip long enough for such purposes. It is desirable, therefore, that in making this class of boxes or baskets that the binding be made 30 of at least two pieces and so manipulated that they may be simultaneously formed and bound to the box body as effectively as is done with a single strip for the small sized boxes.

35 One of the principal objects of the present invention is to provide a machine which is automatic in action and which is adapted to take two narrow strips of binding metal, form them substantially U-shaped in cross-section, and bend the strips transversely 40 about a former or anvil and clench the binding metal thus formed to the folded box body.

Another object of the invention is to provide 45 simple and efficient means whereby two metal strips may be bent about a former from opposite sides thereof and the bent ends of the strip made to overlap so as to form substantially a single binding or rim to adapt the same to be applied to a box body.

Other objects of the invention are to provide 50 a simple and efficient press for simultaneously folding the strips substantially U-shaped lengthwise thereof; to provide

simple and efficient means whereby two strips may be fed the same or different distances; to provide simple and efficient cutting means for the strips; and to provide effective means for simultaneously folding 60 the strips about an anvil or former.

A further object of the invention is to provide simple and efficient means for holding the bent strips about the anvil or former in position to permit a box body to be inserted therein and the binding itself 65 clenched or bound to the box body.

A still further object of the invention is to provide an effective machine for making 70 baskets or boxes which will have a large output and which is adapted to make baskets or boxes of various sizes.

With these and other objects in view, the invention will be hereinafter more particularly described with reference to the accompanying drawings, which form a part 75 of this specification, and will then be pointed out in the claims at the end of the description.

In the drawings. Figure 1 is a plan view, 80 partly diagrammatic and partly in section, of one form of machine embodying my invention.

Fig. 30 is an enlarged sectional elevation of a second form of latch or catch for holding the binding metal about the anvil.

60 Fig. 31 is a view taken on line 31—31 of Fig. 1 showing a part of the guide for the metal binding in advance of the feed mechanism.

Figs. 32 and 33 are views similar to Fig. 31 taken on lines 32-32 and 33-33 of Fig.

1, respectively, but in advance thereof showing how the metal binding is gradually tilted before being cut transversely.

Fig. 34 is a sectional elevation of the tilting rolls; and

Fig. 35 shows a modified form of the feeding means for feeding the formed metal strips.

Fig. 36 is a section taken on line 36-36 of Fig. 37.

Fig. 37 is an end elevation, partly in section, to show more clearly the pawl and ratchet mechanism.

Fig. 38 is a detail section taken on line 38-38 of Fig. 35; and

Fig. 39 is a fragmentary detail central vertical section of the pawl and ratchet mechanism.

In the general construction of the machine shown in the present application, the metal binding is fed as two long strips from separate reels or otherwise or as a strip of double width which is cut lengthwise to form two strips. The two strips are fed lengthwise of the machine on opposite sides thereof to a press which simultaneously bends the two strips lengthwise substantially U-shaped or V-shaped in cross-section. In advance of the press is feeding means for the two strips which is adapted to force the strips forward a determined length and as the strips are fed forward, they are tilted so that one side assumes substantially a vertical position. The strips are cut transversely the proper length which permits the ends of the strip when bent to overlap slightly at their meeting edges. The two strips are fed the desired lengths through the guides and between the tilting rolls into the jaws of the bending means and after being cut by the cutting means, the bending means bends the two strips toward each other on the sides of a substantially rectangular anvil or former corresponding to the shape of the box or basket to be made, and during such bending, moving two of the ends of one of the strips downward to permit the ends to pass under the ends of the other strip to overlap the same properly, the said strips as thus bent to form a rim being suitably supported on the anvil ready to receive the body or box-form. During the forming and bending of the binding, shooks arranged in different magazines are automatically removed and placed in receivers of a rotary carrier so as to lie crosswise of each other. The shooks in this crosswise position are moved between the die and punch of punch and die mechanism, which mechanism is adapted to take the shooks and fold them without breaking into the form of the completed box, and during the forming of said box or box-form, the box body is forced upward into the binding or rim while still supported on the anvil or former. As soon as

the box body is properly inserted in the binding or rim, suitable clencher mechanism located adjacent to the anvil and about the punch is made to clench the metal binding about the box body after which the box body is removed in any suitable way and may be again placed in the carrier and conveyed from the machine or automatically ejected therefrom and stacked.

10 While the invention is shown as employed in connection with a machine of the automatic character described, it will be understood that many of the parts may be used in connection with a hand-operated machine 15 or in a machine of a construction differing from that set forth herein.

The frame 10 of the machine may be of any suitable form and located at any convenient point thereon is a press 11. The press 11 has two narrow strips or ribbons 12 and 12^a of any suitable material usually tin or galvanized iron, which may be supported by or fed to the machine in any convenient way, or the said strips may be wound from spools or reels. The press 11 is adapted to fold the two strips lengthwise thereof simultaneously substantially U-shaped or V-shaped in cross-section and comprises essentially two heads 13 and 13^a with parts of which coöperate movable blades or members 14 and 14^a respectively, the latter being adjustably held by screws 15 or otherwise to a reciprocatory cross-head 16. The parts of the press located in the heads 13 and 35 13^a are substantially the same and the parts coöperating therewith mounted on the cross-head are likewise similarly constructed. The parts mounted in the heads 13 and 13^a each have a plurality of metal plates 17 and 40 17^a of a bar-like form located on opposite sides of a center plate or bar 18 which latter is yieldingly held to move vertically. The plates or members 17, 17^a and 18 as well as the members 14 and 14^a, are substantially identical and operate in the same manner as in my Patent No. 1,154,970, but as a single press. The cross-head 16 is suitably guided to move vertically in the frame 10 and at the lower end thereof is connected to arms 45 19. One end of each arm 19 is pivoted, at 20, to a bracket 21 on the frame 10, the other end being provided with a trundle or roll 22 which is adapted to be operated by a cam 23 on the drive shaft 24. As the shaft 24 is rotated, the cams 23 will move the arms 19 and cross-head 16 causing the members 14 and 14^a to be forced upward so that both strips will be simultaneously folded lengthwise substantially U-shaped or V-shaped in cross-section as set forth in the said application.

As a means for feeding the strips to and from the press, I arrange in advance of said press suitable feeding mechanism 25. This feeding mechanism may be variously con-

structed. As shown, there is a shaft 26 which is held in the outer end of arms 27, the latter being pivotally held, at 28, to brackets 29 forming a part of the frame of the machine. The free ends of the arms 27 are normally forced downwardly by springs 30, one end of which is secured to the arms and the other end to a part of the brackets 29. On the rod or shaft 26 on opposite sides thereof and adjacent to but over the sides of the machine frame are grooved wheels or elements 31 which are adapted to co-operate with rotary elements or wheels 32 having ribs 32^a which enter the grooves in the wheels 31 and between which wheels 31 and wheels 32 the folded metal strips pass. The wheels 32 are supported on a shaft 33 arranged in vertical alinement with the shaft or rod 26. The grooved element or wheel 31 and the wheel 32^a are held to spur gears 34 and 36, respectively, and rotate in unison therewith on the stationary shaft or rod 26 and 33, said grooved wheel 31 being prevented from moving lengthwise of the shaft 26 by collars 35. The gears 34 are each in mesh with the spur gears 36, the latter being secured by screws or otherwise to the ribbed elements or wheels 32. The gears 36 are each held to or formed as a part of one member 37 of a clutch 38, the member 39 of each of said clutches being held to rotate with a pinion 40. Each pinion 40 is adapted to mesh with the teeth of a vertically reciprocatory rack 41. The racks 41 are each suitably guided in the frame or brackets located thereon. At their upper ends the racks are angular in form, as at 42, in which are arranged adjustable stops 43 in the form of bolts or screws which are adapted to engage parts 44 of the brackets 29. The lower ends of the racks 41 are reduced and are guided in sockets 45 of a cross-head 46, the latter being guided between the sides of the frame. The racks 41 are normally forced downward by springs 47, one end of each of which is secured to one of the racks and the other end to a fixed part of the frame, while the racks are moved against the tension of the springs 47 during the vertical movement of the cross-head 46. This cross-head 46 is connected by one or more links 48 to the outer end of an arm 49. This arm 49 is pivoted, at 50, to a bracket on the frame and has a trundle 51 which is adapted to be engaged by a cam 52 on the drive shaft 24, the said arm 49 being normally forced downward by means of a spring 53 or otherwise. As the racks 41 are independently adjustable, different distances of feed or the same feed if preferred for the two strips of binding metal may be obtained. The downward movement of the racks 41 is limited by the screws or bolts 43 and as the lower ends of the racks are free to move in the sockets 45, the cross-head 46 may move 130

a certain distance before it operates and moves one of the racks 41 and then further movement may operate the second rack. It will be noticed in Fig. 2 that the rack at the 5 right hand will be operated a greater distance than the one on the left hand because the cross-head or the socket piece 45 will engage the lower shoulder of the rack on the right hand before the socket on the left 10 hand engages the shoulder of the rack on that side of the machine. In this way a very nice adjustment may be secured which may vary in extent and in which the feed of the two strips may be the same or the extent 15 of feed of one strip made to exceed that of the other.

Each of the strips of metal binding is tilted so as to present one side substantially vertical in order that the strips may be bent 20 properly about the anvil or former and that it may be in position better to receive the folded shooks forming the box body prior to being clenched or bound thereto. As shown, the frame may support two guide 25 bars 54 and 54^a which are held together by screws 55 or otherwise to form a lengthwise channeled guide for the metal strips on opposite sides of the machine. The guides have channels 56 which are adapted to vary 30 in shape lengthwise of the guides. As shown in Fig. 31, the guide channels or grooves 56 receive the strips in substantially the position it is formed by the press. At the section where Fig. 32 is taken and as indicated in Fig. 1, the groove may be of a 35 circular form in cross-section, while at the point where the section Fig. 33 is taken, the groove is of the form or shape of the folded metal binding with one side substantially vertical. Located between the points 40 where the sections Figs. 31 and 32 are taken, and forming substantially a continuation of the guides and on opposite sides of the machine, are tilting rolls shown best in Figs. 45 1 and 34. A grooved roll or member 57 is held to rotate on a stud 58 and this stud is held on the outer end of an arm 59, the latter being pivotally held to a bracket or part 50 of the machine frame. A ribbed roll 60 is held to rotate on a stud 61 which is held to the machine frame and said ribbed roll is adapted to coöperate with the roll 57. These rolls are angularly arranged with 55 respect to a vertical plane and the grooved roll 57 is yieldingly forced toward the roll 60 by a spring 62, one end of which may be attached to the machine frame and the other end to a part of the arm 59. The shape of the rib of the roll 60 and the groove of the 60 roll 57 correspond to the shape in cross-section of the folded binding strips, and during the forward feed of the strips, the latter will be caused to be tilted and the tilted strips guided through the guide grooves 56,

there being a set of tilting rolls for each of 65 the strips.

Each strip after it has been fed inward the proper distance and tilted as previously described, is cut transversely the proper length. In Figs. 5 to 10, I show one form 70 of cutting means which may be employed. There is a cutting device or means for each strip but as they are substantially the same in construction, a description of one will answer for that of the other. A bracket or 75 frame 63 has a base 64 and is located forward of the tilting means already described. The frame 63 has its base provided with openings through which the body of bolts 65 are adapted to pass so as to securely hold the frame or bracket 63 to the main machine frame. The heads of the bolts 65 are movable in slots 66 in the machine frame to adapt the frame or bracket 63 to be moved lengthwise thereof in order that the cutting 80 or shearing means mounted thereon may be adjusted for cutting the metal binding the desired length. The frame or bracket 63 has a box-like casing or part 67 which is angularly arranged with respect to a vertical plane. A cutter 68 is adapted to reciprocate in the casing 67. This cutter is disk-like or circular in form and has a plurality of grooved cutting portions 69 about the periphery thereof any one of which is adapted 85 to serve as one member of the cutting means. The cutter 68 is adapted to be rotatably adjusted about the end 70 of a pin or bolt 71 and said cutter is normally held against rotary movement by a screw or pin 100 72, said pin or bolt 71 serving also as a set screw or clamping means for the cutter 68. At the rear of the cutter 68 is a socket piece or reforming block 73 having a groove 74 in the lower edge thereof which is adapted 105 to form a continuation of one of the cutter grooves. This reforming block 73 is connected to a rod 75, the upper end of which is guided in the end of a sleeve or thimble 76 and is provided with lock nuts 77 on the 110 outer end thereof. A spring 78 is arranged around each rod and tends normally to force the reforming block or socket piece 73 downward. A cutter or shearing member 79 is located under the reforming block 115 73 and is adapted to move toward said reforming block, the said member 79 being adjusted to cut properly by a screw 79^a. The cutter member 79 is in the form of a tooth corresponding in shape to the groove 74 in 120 the socket piece 73. This cutter member 79 is held to a rack member 80, the teeth of which are adapted to engage the teeth of a toothed rod 81, said rod having its teeth long enough to permit the rack member and 125 entire box 67 to be moved for adjustment and still maintain engagement between the teeth of the rack and the teeth of said rod.

There is a rack member 82 which also engages the teeth of the toothed rod 81 which is opposed to the toothed member 80 so that on the rotary movement of the toothed member 81, the rack members 80 and 82 will be forced in opposite directions. The rack 82 carries the cutter member 68 as well as the socket piece 73 so that when the metal binding is fed between the same and the two members are brought toward each other through the rotary movement of the toothed rod 81, the cutting edge 83 of the cutter member 79 will be forced past the edge of the cutter 68, the socket piece yielding during this movement, which will cause the binding to be severed. At the time that the strip is severed, the end may be reformed by the block or socket piece 73 and member 79 so that when the strips are bent about the anvil or former the lapped ends will lie substantially flush. As soon as one cutting edge of the cutter 68 becomes worn, the screw 71 is released and the screw 72 moved out and the said cutter member rotated until the next cutter groove 69 is in position when the screws are again adjusted to hold the cutter. This may be repeated so long as any one of the cutter grooves is adapted for use. The toothed rods 81 may be simultaneously rotated in the same direction by any suitable means. As shown, Figs. 1 and 11, one rod has an arm 84 projecting upward therefrom and the other toothed rod or shaft has an arm 85 projecting downward therefrom. These arms are connected by a transversely extending rod 86. An arm 87 projects outward from the arm 84 and said arm 87 is connected to a vertically reciprocating rod 88 which may be operated by a cam or otherwise so that at each reciprocation thereof, the arms 84 and 85 will be rocked to rotate the toothed rods or shafts 81 and thereby move the cutters so as to sever the metal binding strips.

The metal binding strips before being cut off are fed into the jaws of transverse bending mechanisms and are severed while held by said mechanisms. One strip is fed to the mechanism 89 and the other strip to the mechanism 90 and these mechanisms are adapted to be moved transversely of the machine so as to bend the strip partly about a former or anvil 91 to substantially the shape of the box body and in such a way that the ends of the bent strips will overlap and form in substance a single binding for a box body. Except as to several features of the lapper jaws of the mechanism 90 to be pointed out later, the two mechanisms 89 and 90 are identical and operate in the same manner and a description of one except as to such features will answer for the other and like characters will be used to designate similar parts. The mechanism 89

comprises a central member 92 to each end 65 of which is pivotally held a bending jaw 93. There are two of such jaws each of which is provided with a grooved bar 94 corresponding in shape to substantially one-half of the metal binding when viewed in 70 cross-section and which serves as a guide and holder for the metal binding. This bar 94 forms substantially a continuation of a similar bar 95 of the center member 92 so that the strip is guided by said bars substantially throughout its entire length. The member 92 comprises a guide member 96 having a dovetailed part 97 in which the two parts of the member 98 are held. The member 96 carries the bar 95 and to said member is held by rivets or otherwise one part of the member 98, the other part being 75 yieldingly held to the fixed part so as to be forced toward each other by a spring 99, Fig. 25, and the ends of the spring 99 are 80 attached to the lugs 100 and assist in moving the jaws 93 to their open position to receive the strip. Each part of the member 98 has a lug 100 to which is pivoted one of the jaws 93, the said jaws being provided with recesses 101 for proper co-operation with the former or anvil 91, as will be presently described. The jaws 93 are pivotally held, at 102, to arms 103. There are two arms 103 and said arms each have a 95 lug 104 which is adapted to form a stop for a projection 105 extending outward from the jaw 93, a spring 106 being provided tending normally to hold the projection 105 against the stop 104. The arm 103 is hinged or pivoted, at 107, and is formed integral with a guide arm 108. There are two guide arms 108 and each guide arm has a straight surface 109 which is adapted to engage a roll 110, the latter being mounted upon an adjustable bracket 111 secured to a part of the machine frame, the said bracket being adjustable by means of a bolt 112 or otherwise. The pivot 107 extends through a lug or projection 113 of a bracket or support 110. There are two brackets 114 which are secured to the outer ends of a rod or shaft 115. This shaft 115 is mounted in the lower end of projecting arms 116 of a slide frame 117, the latter being guided upon a guide 115 bar 118 which is secured at one end to the projecting part 119 of the frame bracket 120 and at the other end 121 to a frame bracket 122. The bracket or slide 117, arms 116, rod 115 and brackets 114 form substantially a 120 cross-head for the mechanism 89. The slide 117 may be provided with adjustable gibs 123 for taking up any wear that might occur in the slide and the rearward movement of said slide and parts mounted thereon is limited by means of a bolt 124 which passes through and may be locked to a lug on the end 121 of the frame bracket 122. The slide

117 is yieldingly connected by rods 125 to oscillatory arms or levers 126. It will be evident that when said lever 126 is operated, the connection 125 will force the slide 117 along the guide bar 118 and will carry therewith the jaws 94 and intermediate member 92 to which the jaws are pivoted until the said member 92 engages one side of the anvil, as 127, at which time the recesses 101 fit about the corner socket pieces or pins 128 of the anvil or former 91. The cross-head will continue to move while the member 92 remains stationary and this will cause the jaws 93 to be moved on their pivots against the tension of the springs 106 about the corners of the anvil so as to fold the outer ends of the strip on opposite sides 129 of the anvil, the said folded strip being held to the anvil and retained thereon on the return movement of the cross-head and bending jaws.

The grooved bars which initially receive the folded strip are open at one side and when initially received, the lengthwise folded strip is held in the groove at this time by a bar or shutter 130 which is supported by two pivotal arms 130^a, the latter being held to a transversely extending rod 131. This rod 131 is mounted to rotate in brackets attached to the frame bracket 120 and said rod has an arm 132 which is adapted to be oscillated by a cam or otherwise operated lever 133 so that immediately before the member 92 and jaws 93 are moved forward to a folding position to advance the strip against the anvil, the bar or shutter 130 is raised. The folding jaws are provided with retaining fingers 134 to hold the strip in place after the shutter 130 is raised and during the folding operation until the folding is nearly completed, said fingers being pivoted to lugs 135. These fingers have their forward ends 136 extending downwardly and are adapted to hold the strips in the grooved bars 94 of the jaws during the forward movement of the cross-head. The fingers 134 are automatically released just prior to the last part of the folding operation by the engagement of the ends 137 with fixed projecting parts, as cams 137^a, Fig. 11, so that the jaws can continue the remaining short distance to swing the ends of the strip against the anvil and in order to leave the strip on the anvil when the jaws are returned to their normal position, the anvil being notched, as at 137^b, in the sides thereof for the end of the fingers 134 to enter. The fingers 134 are normally pressed to an engaging position by means of springs 138 or otherwise. The bar 95 of the center carrier member of each of the mechanisms 89 and 90, may be alined during the backward movement with the bars 94 of the jaws by engaging with the ends of adjustable screw stops 138^a, Fig. 23, arranged in fixed frame lugs or brackets 138^b.

I have described in detail the action of the mechanism 89 without particular reference to the mechanism 90. This mechanism 90 is substantially the same construction and operates in a similar manner to the mechanism 89 and the same reference letters corresponding to like parts of the two mechanisms are used to indicate like parts, the main difference between the two mechanisms being that the jaws of the mechanism 90 have a part thereof constructed so that the ends of the strip carried by the mechanism 90 as it is advanced toward the former or anvil 91 is adapted to be forced downward so as to lap under the ends of the other folded strip. These jaws of the mechanism 90 I term the lapper jaws, and the mechanism cooperating with the same the lapper mechanism. The lapper jaws 139 are moved forward, as already explained in connection with the mechanism 89, and are normally held against the lugs 104 of the arms 103 by means of the springs 106 as already described. The jaws 139 at their forward ends have vertically movable members 140. These vertically movable members carry a grooved bar 141 for the initial reception of the folded metal strip. This bar is normally in the position shown in Figs. 18 and 19 which would be in alinement with the grooved bar 95 of the carrier or intermediate member 92. The member 140 with the bar has a tongue and groove connection, as at 142, with each lapper jaw 139, and said tongue and groove connection inclines at an angle, as shown best in Fig. 17. The member 140 is pivoted, at 143, Fig. 17, so that its outer end will swing downward and is adapted to carry therewith the outer end of the metal binding so that it may be forced under and into the ends of the strip bent by the mechanism 89, the strips being somewhat longer than is necessary to extend substantially midway of the anvil 91 in order to provide overlapping ends. The members 140 of the lapper jaws 139 are normally forced upward by means of springs 144 arranged around the screws or bolts 145, and said members 140 are adapted to be moved downward during the swinging folding movement for bending the strip about the anvil by means of cams 146, Figs. 20 and 27, of the clenching mechanism in substantially the same manner as disclosed in my Patent No. 1,154,610.

The mechanism 90 has fingers 134 in the jaws for retaining the metal strip in the grooved bar 141 as in the mechanism 89 and also has the initial holding shutter 130 with the supporting arms 130^a as described in connection with the mechanism 89. The rod 131 of the mechanism 90 has an arm 147 which projects downward and this arm is connected by a rod 148 with an arm 149 which extends upward from the shaft 131

of the mechanism 89 so that on the reciprocation of the rod 133, the two rods 131 on opposite sides of the anvil or former 91 will be operated in unison and in opposite directions to adapt the shutter 130 to be raised when the mechanisms are moved to bend the strips about the anvil or former, the mechanism 89 being adapted to move slightly in advance of the mechanism 90, though the two mechanisms may move simultaneously if preferred.

The ends of the metal binding folded about the anvil or former by the mechanisms 89 and 90 may be supported and held in any desired way. As shown, I provide two hooks or latches 150, Figs. 28 and 29, and two others 151, shown in Fig. 30, though this number of either or both forms of latches may vary. The latch 150 is of a fixed character and the latch 151 of a yielding character, there being two of each, the spring latch or catch being adapted to co-operate to hold the strip bent by the mechanism 89, and the latches or catches 150 being adapted to co-operate to hold the ends of the metal binding folded by the lapper mechanism 90. The latch 151 is pivotally held, at 152, in a socket piece 153. This socket piece 153 is adapted to be inserted in a recess or opening convenient to the anvil 91 and may be held therein at the outer end by the end of a plate and may be adjusted outwardly at the rear end by means of a screw 154. The hook or latch 151 has a slot or groove 155 which is adapted to receive the end 156 of a spring 157, the latter tending normally to force the outer end of the hook or latch downward. The outer end of the latch 151 has a curved lower surface 158 and a lip 159 which is adapted to engage under the lower edge of the substantially U-shaped binding strip. As the strip is folded about the anvil or former 91 by the mechanism 89, the ends will engage the curved portion 158 to raise the latch on the pivot to permit the strip to pass by and as soon as the strip is against the anvil, the outer end of the latch will be forced downward by the spring 157 so as to cause the lip 159 of each latch to engage the end of the metal binding. As the ends of the strip folded by the mechanism 90 are forced downward by the jaw members to permit lapping, the latch 150 in such cases does not have to be pivoted but may be of a fixed character. The latch 150 has its lower end provided with a lip 160 which is adapted to engage the under edge of one side of the folded strip and said latch has its body portion 161 held in a socket piece or box 162, the said body 161 being provided with a projecting lug portion 163 to abut against a shoulder 164 of said socket piece. The socket piece 162 fits into a recess adjacent to the anvil or former 91 and may be adjusted outwardly by means of a screw 165. The

box may be held in its adjusted position by means of a tapered screw 166 arranged at one side of the box or socket piece. When the metal binding has been clenched about the box form as will be presently described, 70 the clinching operation will compress the metal binding to such an extent as will release the edges thereof from the engaging lips 159 and 160 of the latches 150 and 151 respectively, so that the binding or metal rim 75 with the box form may be removed.

The anvil 91 and certain parts co-operating with the folding jaws of the mechanisms 89 and 90, is shown in a measure diagrammatic in Fig. 11, and the construction and arrangement thereof is shown more in detail in Figs. 20 to 22 inclusive. The anvil is also shown rectangular and square but it may be oblong or of any other desired form and the mechanism for folding the rim or 85 binding about the same may be correspondingly changed. As shown, the anvil 91 has corner pieces 167 which may be integral with the body or separate therefrom and about which the binding is formed. The anvil is held to a vertically movable head 168. This head 168 may have a sleeve portion 169 about which is an adjustable tubular and sleeve-like stop 170, the lower end 171 of which is adapted to engage the upper 95 edge or surface 172 of said head when the latter is moved to its elevated position as will be presently described. The anvil head 168 is provided with extensions or parts 173 about the same which serve to prevent the 100 rim or binding from being forced about and off the anvil when the box body is inserted therein, and above the head 168 is a casting or member 174 at the four corners of which are socket pieces 175. In the socket pieces 105 175 are the pins 128 which are held thereto by means of screws 177 or otherwise. The pins 128 serve to form bearings for the recesses or sockets 101 of each of the folding jaws and serve as a pivot for said jaws during their swinging movement to bend the binding about the anvil. During the folding operation, the anvil is normally below the clencher mechanism or means which forces the binding about the box body and 110 in the position shown in Figs. 21 and 22, but as soon as the binding or rim is to be bound or clenched to the box body, the head 168 with the anvil will be moved upward by a spring, not shown, or otherwise and until the surface 172 of said head will engage the stop 171 as will be further described in connection with the clencher and box-forming mechanism.

While this invention refers more particularly to means whereby the binding or metal rim is formed and applied to the box body, I have shown in a general way one form of mechanism for making the box body from shooks of wood veneer or other material. 125 130

This part of the mechanism may be automatic in character taking the shooks automatically from magazines and forming the same into box form and placing the box body in position to have the metal rim or binding clenched thereto in substantially the manner disclosed in my Patent No. 1,154,610, or the said mechanism may be of any suitable kind either automatic or operated by hand. As shown in Figs. 1, 20, 21 and 22, the shooks may be arranged in two magazines 178 and 179 from which the shooks are removed in succession by a pneumatic picker 180. This pneumatic picker 180 has a rotary and reciprocatory movement and is provided with a plurality of arms 181 each of which has pneumatic or other devices to remove the shooks and to hold them in pairs crosswise and place them in this crosswise position in a turret or carrier 182. The turret, carrier or holder comprises four receivers 183. This turret is adapted to receive an intermittent rotary movement and is adapted to take the shooks in a crosswise position and place them between the punch mechanism 184 and the die mechanism 185. Each receiver may have fixed members or clips 186 each of which has an overhanging lip 187 under which the shooks are adapted to be forced when deposited therein by the pneumatic picker or device 180 and in such a way that the uppermost shook will not spring or bend far enough to engage the lower shook, the said shooks being adapted to be removed by the punch and die mechanism.

The die mechanism comprises a base or bottom piece 188 and a rubber suction member 189 which is held to a vertically movable tubular member 190 connected to the die head 191. The tubular member 190 is adapted to be connected to suitable pneumatic suction means to adapt suction to be created and destroyed therein so that suction may be exerted on the bottom of the box after being completed for the purpose of stripping it from the punch 184, the bottom of the plate 188 as well as the tubular screw 192 for holding the plate in position being slotted or grooved along the upper surface thereof to permit air to be drawn within the tube or connection 190. Around the bottom or base 188 are four yielding bottom plates 193 and movable about said bottom plates are four wings 194. Each wing 194 has a presser plate or member 195 at the outer end thereof and each wing at its inner end is provided with recesses which are adapted to be engaged by spring-pressed bolts 196, the spring being interposed between the head of said bolt and a lug 197. The wings 194 are connected to arms 198 and these arms are connected by links 199 to the die head and in such a way that during the folding movement of the die, the

wings at their inner ends will move about the edges of the yielding bottom plates 193 with a lapping effect and in such a way that the shooks at the point of fold will be held and prevented from breaking or slivering particularly when the shooks are made of wood. The die mechanism moves bodily upward through one of the receivers of the turret and meets a presser foot 200 of the punch 184. This punch has members 201 and 202, the latter having four yielding sides 203, the latter being forced outwardly by springs 204 and limited in such outward movement by screws 205 or in any other suitable way. Above the yielding sides 203 is the anvil or former 91 about which the metal strips have been formed and which metal strips have been bent substantially rectangular in form to correspond to the shape of the box form with the folded edges downward so that during the upward movement of the die with a part of the punch mechanism which has been moved downward to meet the die to clamp the shooks and which is folded during the upward movement of the die and punch mechanism, will receive the upper edges of the box form.

The binding or rim is adapted to be forced or clenched about the box form by any suitable mechanism. As shown, levers 206 are pivoted, at 207, about the punch and at their upper ends are connected by toggle links 208 to a movable part or sleeve 209 which is adapted to force the lower ends of said levers 206 toward or away from the anvil. At the lower part of each arm 206 is a clencher jaw 210 which when the anvil is moved after receiving the box form to a position in alignment with said gripping jaws, the latter will be operated so as to 105 clench the binding or rim securely to the box body. The clenching is done at the lower edge of the rim of the box body which is necessarily narrow and in such a way as to force the same into the wood and thus make 110 substantially a dovetailed connection with the wood. As the wood is more or less damp when the box body is made, it will diminish in thickness when it becomes dry and will have a tendency otherwise to become loose from the metal rim, but by clenching the rim in the manner disclosed so that the lower edges are bound into the wood to squeeze the wood substantially dovetailed at the upper edge, the wood body 115 cannot become detached from said rim, the latter, during the clenching operation, being released from the latches or hooks 150 and 151 as already described. During the clenching operation, the anvil is raised by a 125 spring or otherwise until the end 171 of the sleeve stop 170 engages the surface 172 of the anvil head 168. The head 168 and member 202 of the punch are forced downward and held in this position to place the anvil 130

in alignment with the folding mechanism by the downward movement of the sleeve 209 engaging the upper end of the sleeve 169 which forms an extension of the anvil head 168. After the box or basket is formed, suction is created in the tubular member 190 which together with the presser foot 200 will strip the box from the punch and will deposit the same in substantially Y-shaped brackets 211 located in the four corners of each receiver 183 of the turret or carrier 182, when on further movement of the turret to place another set of shooks in position to have the box form made, the completed box 10 will be carried away out of the path of the punch and die mechanism in a convenient position for ejecting or other means. The parts as thus described relating to the means for making the box form, are substantially 15 the same as disclosed in my application 20 hereinbefore referred to.

The link connection 125 shown in detail in Fig. 24 for operating the cross-head of the folding mechanisms 89 and 90, may be 25 variously constructed. As shown, it comprises essentially two members 212 and 213 which are yieldingly held together so that it will be impossible for the parts of the mechanism to be broken if the parts are not adjusted exactly when the folding jaws and carrier members are moved toward and against the anvil. The member 212 has a threaded stem 214 and locked to this stem is a sleeve or thimble 215. The stem 214 30 has an opening 216 in which the end 217 of a rod 218 of the member 213 is adapted to slide. On the rod 218 are lock nuts 219 and interposed between the lock nuts 219 and the threaded stem 220 of a member 221 is a 35 spring 222. The sleeve or thimble 215 is held to the threaded stem 220 of the member 221, and said member 221 forms a guide for the outer end of the rod 218. The two members 212 and 213 are therefore connected 40 together so as to form a yielding connection between each cross-head of the folding mechanisms and its operating lever 126.

The operation of the invention will be readily understood from the foregoing description when taken in connection with the accompanying drawings. The two metal strips having been fed into the machine on opposite sides thereof are advanced forward by the feed mechanism the desired distance, 50 the said strips having been bent or folded lengthwise by the press 11. As the strip is advanced forward after being folded lengthwise, it is tilted by the guides and tilting rolls and suitably guided into the folding 55 and lapper jaws of the folding mechanisms 89 and 90. The shutter 90^a is raised and the folding jaws with the cross-heads are moved toward the former or anvil 91 from opposite sides thereof and during such folding 60 movement the jaws will pass about the an-

vil or former, the ends of the strip carried by the lapper jaws 139 of the mechanism 90 being forced downward so as to lap under the ends of the strip folded by the mechanism 89, the ends of the folded strips being 70 held by the latches 150 and 151 as already explained. The box form or body during the time that the folding of the metal binding is taking place, has been proceeding, and said box form when folded by the punch 75 and die mechanism as already explained, will be fed into the binding and clenched thereto by the jaws 210 of the clenching mechanism.

In Figs. 35 to 39, a construction somewhat 80 different from that shown in the other views and particularly in Fig. 2 is provided for feeding two lengthwise folded strips either the same or different distances preparatory to the same being cut and bent around the 85 anvil. This construction is somewhat simpler than that shown in the other figures and ordinarily I prefer to use this construction of feed. It differs from that shown in Fig. 2 primarily in using a different form 90 of clutch or ratchet mechanism and in employing a single rack and pinion instead of two racks and pinions which coöperate with said racks. The grooved members, rolls or wheels 223 are rotatably held upon a shaft 95 224, the latter being carried by pivotally held arms 225. The arms 225 are normally forced downward by springs 226, one end of which is held to the arms and the other ends being held to the machine frame. The 100 springs 226 tend to force the grooved wheels 223 toward the ribbed wheels, rolls or members 227. Each wheel 227 is provided with a gear 228 which is in mesh with a similar gear 229, the latter being movable with one 105 of the grooved wheels or rolls 223 so that the grooved and ribbed wheels may rotate in unison. Each ribbed roll or wheel 227 is provided with a hub or drum portion 230, the inner part of which is provided with 110 ratchet teeth 231 forming an internal ratchet wheel. The ratchet teeth 231 are adapted to be engaged by pawls 232 which are pivoted, at 233, to the outer ends of arms 234. The arms 234 for each wheel form a lever which 115 is held to a transversely extending shaft 235 by means of a key 235^a or otherwise so that when the shaft 235 is rotated or oscillated as will be presently described, the pawls 232 will engage the ratchet teeth 231 120 of each wheel 227 and will rotate the same about the shaft 235. There are two pawls for each wheel 227. The pawls are arranged diametrically opposite each other and each pawl is normally forced to an engaging position by means of a spring 235^b one end of which is seated in a recess in the pawl and the other end in a recess in the pawl-carrying arm 234.

The ribbed wheels 227 are loosely mounted 130

upon the shaft 235 and are held against lengthwise movement on said shaft. A pinion 236 is held to the shaft substantially midway between the gears 228 and adapted 5 to engage said pinion is a toothed rack 237. This rack is adapted to move vertically and may be reciprocated by any suitable means such for example as links 238. As the rack 237 is reciprocated, it rotates the pinion 236 10 and this will rock the shaft 235 and move the pawl-carrying arms 234. This will cause a rotary movement to be given to the ribbed wheels 227, which, owing to the intermeshing gears 228 and 229, will impart a 15 like rotary movement to the grooved wheels 223.

As a means for regulating the extent of movement of the feed rolls, the pawls 232 may have their engagement with the teeth 20 231 regulated. This may be secured in various ways. As shown, a lever or element 239 for each set of pawls is loosely mounted upon the shaft 235 and each outer end of said lever carries a cam portion 240 upon 25 which the pawls 232 may ride for a part of their movement. Each lever 239 has a slotted extension 241 through which passes a pin or bolt 242. The bolt 242 extends through a lug 243 on a part of the machine 30 frame so that by means of said bolt, the position of the lever 239 and the cams 240 may be changed relatively to the normal position of the pawls 232. By moving the cams 240 away from the pawls, the latter will engage a greater number of teeth and consequently a greater throw or movement will 35 be imparted to the feed rolls, and the reverse takes place when the cams are moved toward the pawls, for in that case the pawls in their 40 movement in one direction will be disengaged sooner from the teeth 231, and the means for disengaging the pawl by the cam 240 being more clearly shown in Fig. 38. By shifting the cams 240 on one side of the 45 machine differently from the cams on the other side of the machine, the feed rolls or wheels will be moved different distances and different extents of feed will be obtained for the binding metal, while by having the 50 cams on both sides of the machine similarly adjusted with respect to the pawls 232, the same extent of feed of the metal binding is obtained.

From the foregoing, it will be evident that 55 effective means is provided whereby large baskets or boxes for fruit may be made automatically and a binding applied thereto as a single element which is composed as a plurality of independently fed and bent metal 60 strips; that effective means is provided for folding and bending the strips and for holding the same about an anvil or former; that simple feeding and cutting mechanism is provided whereby the strips may be fed the

same or different distances and the said 65 strips held and cut while engaged by the folding mechanism; that effective folding mechanism is provided on opposite sides of the machine for each strip; that said mechanism is so constructed that the strip may be 70 folded about a rectangular anvil or former and the ends made to overlap; that said mechanism is so constructed and operated that it permits the box body to be formed automatically and the binding applied to 75 said body; and that said mechanism while shown and described as adapted particularly for machines wherein the entire basket is made automatically, the said mechanism or parts thereof may be of such a character 80 so that they may be employed in various connections and for making boxes of various sizes.

Having thus described my invention, I claim as new and desire to secure by Letters 85 Patent:—

1. In a box-making machine, the combination of means for supporting two narrow metal strips and for bending said strips, a grooved rotary member for each strip, a ribbed rotary member coöperating with the rotary member to feed each strip lengthwise, gears for rotating the members in unison, means for operating one of said members, a pinion for operating said latter 95 means, a rack engaging said pinion, means for reciprocating the rack, and means whereby the rotary members may be moved the same or different distances.

2. In a box-making machine, the combination of means for supporting two metal strips and for bending said strips, a grooved rotary member for each strip, a ribbed rotary member coöperating with the rotary member to feed each strip lengthwise, gears 100 for rotating the members in unison, clutches for operating one of said members, pinions for operating said clutches, racks engaging said pinions, springs normally forcing the racks in one direction, stops for limiting the 105 movement of the racks in the opposite direction, and means for moving the racks against the tension of the springs.

3. In a box-making machine, the combination of means for supporting two long 115 metal strips, means for feeding the strips, means for folding the strips lengthwise, means for folding the strips transversely, cutting means for cutting the strips transversely while held by the transverse folding 120 means, means whereby the cutting means may be independently adjusted, and means for simultaneously operating said cutting means.

4. In a box-making machine, the combination of means for supporting two long 125 metal strips, means for feeding the strips, means for folding the strips lengthwise,

means for folding the strips transversely, cutting means for cutting the strips transversely while held by the transverse folding means, and means whereby the cutting means may be independently adjusted lengthwise of the strips.

5. In a box-making machine, the combination of means for supporting a metal strip, means for feeding the strip, means for 10 folding the strip lengthwise, means for folding the strips transversely, cutting means for cutting the strip transversely while held by the transverse folding means, and means whereby the cutting means may be adjusted 15 lengthwise of the strip.

6. In a box-making machine, the combination of an anvil, two carriers movable from opposite sides thereof and each adapted to support a metal strip, a pivoted jaw held 20 at each end of each carrier, an arm pivotally held to each jaw and having a stop thereon, springs normally forcing the jaws against said stops, a guide forming a part of said arm at each side of each carrier, adjustable brackets carrying rolls engaged by 25 said guides during the movement of the carriers, a cross-head to which the arms and guides of each carrier are pivotally connected, an oscillatory lever for each cross-head, a yielding connection between each 30 lever and said cross-head adapted to move said cross-head so as to force the jaws inward toward the anvil to cause the strip carried thereby to be bent about the anvil, 35 and means for clenching the metal strips about a body.

7. In a box-making machine, the combination of an anvil, two carriers movable from opposite sides thereof and each adapted 40 to support a metal strip, a pivoted jaw held at each end of each carrier, an arm pivotally held to each jaw and having a stop thereon, springs normally forcing the jaws against 45 said stops, and means for moving the arms, jaws and carriers to bend the strips about the anvil.

8. In a box-making machine, the combination of an anvil, two carriers movable from opposite sides thereof and each adapted 50 to support a metal strip, a pivoted jaw held at each end of each carrier, an arm pivotally held to each jaw and having a stop thereon, springs normally forcing the jaws against 55 said stops, a guide forming a part of each arm, a cross-head to which the arms of each carrier are connected, means for moving the

cross-heads, and means for clenching the metal strips about a body.

9. In a box-making machine, the combination of an anvil, two carriers movable 60 from opposite sides thereof and each adapted to support a metal strip, a pivoted jaw held at each end of each carrier, an arm pivotally held to each jaw and having a stop thereon, 65 springs normally forcing the jaws against said stops, means for guiding said arms, a cross-head to which each pair of said arms are pivotally connected, means for operating said cross-heads, and means for clenching the folded metal strips about a body. 70

10. In a box-making machine, the combination of an anvil, two carriers having grooved bars adapted to receive metal strips, jaws pivotally held to said carriers and having grooved portions adapted to form a continuation of the grooved bars of said carriers and adapted to hold the same metal strips, shutters adapted initially to hold the strips in the carriers and releasable when the carriers are moved, means for releasing 80 the shutters, fingers mounted upon the jaws one for each jaw adapted to retain the metal strips during the movement of the carriers and jaws, means whereby the grooved portions of two of the jaws have a vertical 85 movement, means for automatically releasing the jaw fingers, and means for moving the carriers and jaws.

11. In a box-making machine, the combination of an anvil, means for bending a 90 metal strip to form a binding about said anvil, a socket piece located near the anvil, a pivotally held latch having a lip at one end arranged in said socket piece, means for adjusting said socket piece and for holding the 95 same in its adjusted position, and a spring normally forcing the latch in one direction.

12. In a box-making machine, the combination of an anvil, means for bending a metal binding about said anvil, a fixed latch 100 having a lip adapted to engage a part of the binding, a socket piece in which said latch is held, means for adjusting and holding the socket piece adjacent to the anvil, and 105 clenching mechanism for releasing the binding from the lip of the latch.

This specification signed and witnessed this 11th day of March A. D. 1915.

CHARLES BURNHAM.
